MEANS AND METHOD FOR FILLING AND
CLOSING CONTAINERSGeorge Arlington Moore, Louisville, Ky., assignor
to Humoco Corporation, Louisville, Ky., a cor-
poration of Delaware

Application April 25, 1936, Serial No. 76,437

16 Claims. (Cl. 226—73)

This invention relates to the art of packaging commodities and more particularly to container closures and to a method and means for packing materials of a non-fluid nature in a container 5 constituted of fibrous and/or metallic materials and forming said closures.

One of the objects of the present invention is to provide a novel method for filling and packing a container and sealing the open end thereof, whereby the sealing of the open end of the 10 filled container may be carried out while the container is supported in a horizontal or any other suitable or desirable position.

Another object is to provide novel apparatus 15 adapted for use in packing a non-fluid material in a container whereby the packing plunger is not contaminated and wastage of the material resulting from the packing operation is eliminated.

A further object is to provide a novel method 20 and means for filling and sealing a container whereby that portion of the container body which forms part of the seal is not contaminated during the filling and packing operation by the material with which the container is filled.

Another object is to provide a novel method 25 for packaging materials whereby a treated portion of the inner walls of the container for said materials is protected against contamination by the material.

Still another object is to provide a container 30 having novel secondary closure means in combination therewith which may be readily inserted therein, rendering it possible to handle the container freely in any desirable position without spilling or disturbing the material with which the container is filled.

A still further object is to provide a novel 35 means and method for packing and hermetically sealing materials in a container which is originally fabricated with an opening therein having the same dimensions as a cross-section of the container body.

The above and further objects and novel features of the invention will more fully appear from the following detail description when taken in connection with the accompanying drawings. It is to be expressly understood, however, that the 40 drawings are for the purpose of illustration only and are not designed as a definition of the limits of the invention, reference being had primarily for this latter purpose to the appended claims.

55 In the drawings, wherein like reference char-

acters refer to like parts throughout the several views,

Fig. 1 is a sectional isometric elevation of a container and parts of the novel apparatus which may be employed in carrying out the method of 5 the present invention;

Fig. 2 is a side elevation, partly in section, of the container and the parts of Fig. 1 supported on a vibrator;

Fig. 3 is a similar view, partly in section and 10 with parts broken away, showing the container in position for packing and the reception of a secondary closure member;

Fig. 4 is a similar partial view, on an enlarged 15 scale, illustrating the packing and closure insert- ing plunger in an intermediate position;

Figure 5 is a partial sectional view showing the 20 secondary closure in operative position, and,

Fig. 6 is a sectional isometric elevation of the 25 completed package after packing and sealing.

The novel container and method comprehended by the present invention and one form of apparatus for practicing said method are, by way of example, illustrated in the drawings and herein-after described in one of their great variety of 30 applications in the packaging art, i. e. in the adaptation thereof to the packaging of loose, finely-cut tobacco, also highly "cased", in a container comprising fibrous materials, said container being oblong in cross-section and formed 35 with an open end through which the tobacco may be inserted. The method of the invention may of course be employed in packaging many other materials or commodities in containers which may have practically any desired shape 40 and which may be constituted by other than fibrous materials, said method consisting broadly in filling an open-ended container while protecting the marginal walls thereof and placing a secondary closure therein to permit free han- 45 dling of the same during the operation of securing a permanent closure in the open end thereof.

In the specific embodiment of the invention 50 illustrated, the container comprises a body portion 10 which is preferably fabricated from one or more blanks of fibrous materials such, for example, as paper, fiberboard, or the like. If a laminated body is desired, the various layers thereof may be bound together by any suitable adhesive, or solvent activated cements, and the inner and outer surfaces may be coated with thin, dry films of moisture-proof lacquers or the like, the inner coating preferably having thermo- 55 plastic adhesive qualities for a purpose to appear

hereafter and the outer coating having a high gloss.

Body 10, as shown, is oblong in horizontal cross section, the same having a pair of straight parallel side walls 11, 11 connected by arcuate portions 12 (Fig. 5). A pair of external grooves 13 and 13', having complementary internal ribs 14 and 14', respectively, are formed in each of said side walls adjacent the upper and lower ends 10 of body 10 without disturbing the shape of marginal portions 15 and 15', that is, those portions of the body between said grooves and the upper and lower edges thereof. Ribs 14, 14' are preferably constituted by a horizontal ledge portion 16, a vertical portion 17, and an angular portion 18 which joins the side wall of the body and said vertical portion, but the same may take other shapes and may extend throughout the entire periphery of body 10 or be interrupted at 20 desired intervals.

After the formation of body 10, a head, constituting a top closure, is inserted and sealed in one end thereof, said head in the form shown being so constructed that an opening through 25 which the contents of the container may be dispensed can be made therein by digital pressure. As best seen in Figs. 1 and 6, said top closure comprises a central portion 19, a peripheral flange 20 which engages the inner surface of margin 15', and a rib 21 which joins said central portion and flange and engages ledge 16 of rib 14'. Margin 15', which, as heretofore pointed out, has a thin, dry coat of thermoplastic lacquer on the inner surface thereof, is flowed 30 or curled into overlapping relation with flange 20 and pressed into intimate contact therewith. Heat may be applied to seam 15', 20 during the pressing operation to activate said thermoplastic adhesive or solvoplastic lacquer having adhesive 35 qualities, and permit the same to flow under the application of pressure into the interstices of the fibrous material to thereby weld the engaging plies together forming an hermetic seal. The central portion 19 of the top closure may be 40 scored at 22 without destroying the impermeability thereof and thus provide a frangible hatch which can be broken by digital pressure to form an opening through which the contents of the container may be dispensed. Closure 19, 20 may 45 be drawn from a blank of fibrous materials or, if desired, from a blank comprising fibrous and foil laminations. Any other suitable type of closure may, of course, be employed in lieu of the preferred form above described, and the same 50 may be secured to the container in any of many well known ways.

The open ended container thus fabricated may 55 now be filled with any desired material or commodity 23, such, for example, as smoking tobacco, the same being poured into the container through the open end or bottom thereof and pressed therein by a suitable plunger. In order, however, that a head or bottom closure similar to top closure 19, 20 may be inserted in the container after said filling and packing operation, and a hermetic seal formed between said closure and the marginal portion 15 by a solvent or heat activated adhesive placed on the inner surface 60 of the latter, it is highly desirable that the treated walls of said margin be protected from contamination or fouling by the tobacco or other material. Additionally, it is desirable that the tobacco or other commodity be prevented from 65 accumulating on ledges 16 of ribs 14 which serve

as a seat for a permanent closure which may be similar to closure 19, 20.

Novel shielding means are provided for attaining the above desirable results and as shown such means comprise a tubular member 25 having the same general shape in horizontal cross section as body 10 but with smaller dimensions, the width of the shield preferably being approximately the same as the distance between the inner surfaces of vertical portions 17 of ribs 14. Said shield or member may be constructed of any suitable material, preferably a light-weight, substantially rigid material such as metal, and is adapted to be telescopically received by body 10 so that the lower edge thereof contacts or is adjacent to the inner portions of ledges 16, the inner surface of the shield being flush with vertical portions 17. The upper end of the shield extends beyond the edge of body 10 and is provided with a supporting and positioning flange 20 26. It will thus be seen that the treated walls of margin 15 will be protected by shield 25 against contamination to thereby preserve the adhesive film thereon and also that the possibility of any particles lodging on ribs 14 and interfering with the insertion of a closure member is obviated. To facilitate the placing of material in the container, a suitable funnel may be provided, the same, as shown, being constituted by a flared upper portion 27 and a lower portion 30 35 28 which is adapted to be telescopically received by shield 25.

When the desired quantity of loose tobacco or similar material has been poured into funnel 27, 28 and through shield 25, the upper level 35 thereof before packing will ordinarily, in practice, be above the plane of the edge of body 10 and even above the upper edge of shield 25. In order to pack the filling material, the container, together with said funnel and shield, is preferably next placed on a vibrating machine which may be of the usual or any suitable or desirable construction, the illustrated embodiment of the same comprising a socket 29 in which the container may be inserted, said socket being secured 40 to a vibrating plate 30 mounted on a plurality of springs 31 that are in turn supported by a frame 32. The vibration of plate 30 brings about an even distribution and settling of the tobacco in the container, causing the level thereof to move 45 down to a position substantially as shown in Figs. 2 to 4. Since the vibrating means do not per se constitute any part of the present invention, it is believed to be unnecessary to show and describe the same in further detail. 55

It is now necessary to further press or pack the tobacco into body 10 to permit the insertion of a bottom closure in the container, and heretofore in the filling of open ended containers this operation has, to the best of my knowledge, been 60 carried out by moving a power operated plunger into direct contact with the tobacco or other commodity being packed in said open ended container. When this is done, however, a large number of the moist or "cased" tobacco particles invariably adhere to the plunger and are withdrawn from the container. Due to the vibration of the machinery, jarring of the plunger, air currents, and other causes, these adhering particles fall from the plunger after removal of the container and contaminate the machinery, thereby causing operating failures and rendering frequent cleaning thereof necessary. Such method also results in large quantities of 65 tobacco being unnecessarily wasted. Further- 70 75

more, the tobacco, being of a spongy nature, does not retain its compressed position after withdrawal of the plunger, particularly if the container is subjected to jarring or rough handling, but rather tends to rise above the level to which the same is pressed by the plunger, thus necessitating larger containers for a given quantity of tobacco. Additionally, it becomes necessary to handle the container in an upright position to prevent spilling of the contents until a bottom closure is secured in place.

In order to obviate such contamination and wastage, to counteract the sponge action of the tobacco with the attendant disadvantages, and to render it possible to handle or support the container in any desirable position during the subsequent steps of inserting and sealing a permanent closure member therein, the method of the present invention includes the step of inserting a secondary closure member into the container in a novel manner simultaneously with the packing operation. Said step is preferably carried out in the manner illustrated in Figs. 3 and 4 wherein the container 10, in addition to being supported by a platform 33, is also positioned and supported by chucks 34 and 35 which have ribs adapted to coat with grooves 13 and 13', respectively. Shield 25 is held against downward movement and in a central position with respect to body 10 by a plate 36. A flat closure member 37, having substantially the same dimensions as the inner periphery of body 10 and hence the same as the opening therein, is supported by a plate 38 in a position directly above the open end of said body and below a plunger 39, said supporting plate having an opening therein of sufficient size to accommodate the plunger.

Plunger 39 is shaped similarly to body 10 and shield 25, but the dimensions thereof are slightly less than the inner dimensions of said shield so that the same may be reciprocated therethrough. The lower or operating face of said plunger is in effect convex along both its longer and shorter dimensions, said face being preferably formed by a longitudinal rib 40, the ends of which curve downwardly toward the center of the plunger from the rounded ends of the latter and by a plurality of laterally extending arcuate ribs 41 of which there are preferably two that taper downwardly toward the center from the straight parallel sides of the plunger. When plunger 39, which operates in a guide 42, is moved downwardly either by manual or power means, closure 37 is pushed thereby through the opening in plate 38 and into shield 25. Said closure, being larger than the inner periphery of shield 25, is forced to assume a curved contour corresponding to the lower surface of ribs 40, 41, such curvature, however, being insufficient to break down the fibers of the closure card and impair the inherent resiliency thereof, but sufficient, on the other hand, to permit the same to enter shield 25 without forming a flange at the outer edge thereof. The lower outer corner of the edge of said closure bears against the walls of shield 25 with sufficient force to act as a scraper, thereby insuring that every particle of tobacco or other commodity will be carried downwardly into the container.

It will be apparent that the downward movement of plunger 39 with member 37 acting as the operative face thereof is effective to pack material 23 in body 10. When the edges of closure 37 reach a plane below ribs 14, which are reinforced during the packing operation by chuck

34, plunger 39 is withdrawn. The edges of said closure thereupon engage the lower angular portions 18 of ribs 14 and, by reason of the natural resiliency of the material of member 37, assisted in the present instance by the sponge action of the tobacco, the center of said closure is sprung upwardly until the same assumes a substantially flat position, as seen in Fig. 5. Member 37 thus serves not only as a temporary operating face for packing plunger 39 to prevent the adherence of tobacco particles on the latter and as a scraper for the walls of shield 25, but also as a secondary closure which holds the tobacco or other filling material in packed condition in body 10 and permits handling of the latter in any desirable position before and during the insertion of the permanent closure. This latter advantage is of importance due to the fact that the machinery for inserting and sealing the permanent head or bottom closure in the container 20 may be greatly simplified if the operation can be carried out while the container is supported in a horizontal rather than a vertical position. Additionally, closure 37 prevents any of the filling material from being thrown out against the 25 walls of margin 15 after shield 25 is removed and contaminating the thermoplastic lacquer or other adhesive thereon or lodging on ribs 14.

The next and final steps of the method of the invention consist in inserting a flanged closure 30 member 43 in the open end of body 10 against ribs 14, flowing the marginal portion 15 into interlocking relation with the flange 44 of closure 43, and applying heat and lateral pressure to the 35 interlocked marginal portion and flange to activate the thermoplastic adhesive lacquer between the engaging surface of the interlocked plies, which adhesive has been protected by shield 25 and closure 37 against contamination, and press the activated lacquer into the interstices of the 40 materials constituting said body and closure, thereby substantially welding the plies together and forming a fluid and air tight seal. Closures 43, 44 and 19, 20 may both be inserted and secured in body 10 in substantially the same manner by any suitable apparatus such, for example, as that shown and described in my copending application Serial No. 53,722, filed December 10, 1935. A method and apparatus for fabricating the container body are also disclosed in 50 said prior filed application.

There is thus provided a container and novel closure means therefor and also a novel method and means whereby a material may be readily and inexpensively packed and sealed in said container in an air and fluid tight manner with a minimum of wastage during the filling and packing operations. In the packaging of certain types of materials, i. e. those which tend to expand when released after exercise of pressure thereon, the novel container and method of the present invention permit the packing of a larger quantity of said materials in a given container than has been possible heretofore. Additionally, simplified packaging machinery may be employed 60 in carrying out said method.

Although only one embodiment of the novel container and apparatus for carrying out the method of the invention has been illustrated and described, it is to be expressly understood that other sizes, shapes and forms of containers and closures therefor may be employed and that various changes may be made in the apparatus herein described without departing from the spirit and scope of the invention, as will now 75

be apparent to those skilled in the art. The method of the present invention is of special utility in packaging tobacco, such as highly cased pipe tobacco. When the container is opened, 5 the tobacco is easily sifted into the pipe or hand, due to the manner in which the package is filled, and it is unnecessary for the user to probe the tobacco out with his finger. Reference is had primarily to the appended claims for a definition 10 of the limits of the invention.

What is claimed is:

1. The method of packaging material which consists in fabricating an open ended container having an internal rib in the side wall adjacent 15 the open end thereof, filling the container with said material, and inserting a closure member therein having dimensions substantially equal to the inner periphery of said container to a position whereby the same will be held against removal by said internal rib.

2. The method of packaging material which consists in fabricating an open ended container having an internal rib in the side wall adjacent the open end thereof, filling the container with 20 said material, inserting a secondary closure member therein having dimensions substantially equal to the inner periphery of said container to a position whereby the same will be held therein by said internal rib, placing a flanged closure in said open end exterior of said secondary closure, and adhesively joining the flange of said closure and the marginal portion of said container.

3. The hereindescribed method of packaging material in an open ended container having internal ribs in the side wall adjacent the open 35 end thereof and a marginal portion between the ribs and the edge of the container which consists in placing a shield in the open end of said container to cover the inner walls of said marginal portion, filling the container by pouring the material through said shield, inserting a secondary closure through said shield to a plane below said ribs whereby the same is held against 40 withdrawal, removing said shield, and securing a permanent closure in said open end exterior of said secondary closure.

4. The hereindescribed method of filling and sealing an open ended container body having an internal bead in the side wall thereof which consists in filling said container with material to be 50 packaged, placing a secondary closure in the open end of the container body in a position to be held therein by said internal bead, placing another closure in said open end of the container body, and interlocking the edges of said last-named closure and the container body to permanently secure said last-named closure therein.

5. A fibrous container filled with material to be preserved having an internal rib in the side 55 wall adjacent the end of the body thereof through which said material was inserted, a secondary closure held against removal from the body by said rib, and a permanent closure in said end seated on said rib and united with the container by means of a closure seam formed by the interlocked edges of said permanent closure and the container body.

6. A fibrous container filled with material to be preserved comprising a container body having 60 an internal rib in the side wall thereof adjacent the end through which the material was inserted, a flat closure in said end having substantially the same dimensions and surface area as a cross section of said container and being held against the inner side of said rib by said material,

and a flanged closure in said end seated on the outer side of said rib and united with the container walls by a thermoplastic adhesive.

7. The method of packaging material in an open ended container having an internal bead in 5 the side wall adjacent the open end thereof which includes filling the container with said material, and simultaneously compressing said material and inserting a flat closure of the same size and outline as said open end to a plane below said 10 bead while holding said container by means having a portion extending into a groove complementary to said internal bead.

8. The method of packaging material in an open ended container having an internal bead 15 in the side wall adjacent the open end thereof which consists in filling the container with said material, simultaneously compressing said material and inserting a flat closure member of the same size and outline as said open end to a plane 20 below said ribs, placing a flanged closure member in said open end, and permanently securing said flanged closure member to the container wall.

9. The method of packaging material which 25 consists in fabricating a container having an open end, treating the inner walls of the marginal portion of the container adjacent the open end thereof with a thin dry film of thermoplastic adhesive, filling said container while 30 shielding said treated wall portion, placing a flanged closure in said open end, and joining the flange of said closure and said treated wall portion by the application of heat and pressure thereto.

10. The method of packaging material which 35 consists in fabricating a container having an open end, treating the inner walls of the marginal portion of the container adjacent the open end thereof with a thin dry film of thermoplastic adhesive, filling the container with said material while shielding said treated wall portion, simultaneously packing said material into the container and inserting a flat closure member therein, retaining said closure in the container 40 by causing the same to engage an internal bead in the wall of the latter, and placing a second closure in said open end and securing the same 45 therein with said adhesive.

11. The method of filling and closing an open 50 ended container having an internal bead in the side wall adjacent the open end thereof which consists in injecting the material to be packaged into the container through a shield telescopically received by the marginal portion of the open 55 end of said container between said end and bead, and simultaneously packing said material in said container and inserting a flat closure therein, the inner surface of said closure being in contact with said material and held against removal from 60 the container by said bead.

12. The method of filling and closing an open ended container having an internal bead in the side wall adjacent the open end thereof which consists in injecting the material to be packaged, 65 into the container through a shield telescopically received by the open end of said container, simultaneously packing said material in said container and inserting a flat closure therein, the inner surface of said closure being in contact with said material and held against removal from the container by said bead, placing a flanged head in said open end, and securing the flange of the head and the wall of said body to one another.

13. The method of packaging material which 75

consists in fabricating an open ended container having an external groove and an internal rib complementary to said groove, holding said container externally by means cooperating with said groove, filling the container with said material, and inserting a flat closure in the container below said rib, said closure being of the same size and outline as the open end of said container.

14. The method of packaging material which consists in fabricating an open ended container having an external groove and an internal rib complementary to said groove, holding said container externally by means cooperating with said groove, filling the container with said material, inserting a flat closure in the container below said rib, said closure being of the same size and outline as the open end of said container, placing a flanged closure in said open end, and interlocking the marginal portion of said container 20 and the flange of said flanged closure.

15. In apparatus for packing materials in an open ended container, the combination of a tubular shield having the same shape as the container

and adapted to be telescopically received thereby, means for supporting said shield centrally of the open end of said container, means for supporting a closure for said container, a plunger movable through said shield to simultaneously compress said material and move said closure through the shield into the container, and means exterior of said container for supporting the same, said last-named means having a rib adapted to cooperate with an external groove in said container.

16. The method of packaging material which consists in fabricating a container having an open end and an internal rib adjacent said end, filling the container with said material, subjecting the container to vibrations to settle said material, and simultaneously packing said material in the container and inserting a flat closure member therein having dimensions substantially equal to the inner periphery of said container to a position whereby the same will be in contact with 20 said material and held against removal by said internal rib.

GEORGE ARLINGTON MOORE.
